(57) **CLAIM**

The ornamental design for a flexible draw latch, as shown and described.

DESCRIPTION

FIG. 1 is a perspective view of an embodiment of a flexible draw latch embodying the new design;

FIG. 2 is a top plan view thereof;

FIG. 3 is a bottom plan view thereof;

FIG. 4 is a right side elevational view thereof, the left side elevational view being a mirror image of the right side;

FIG. 5 is a front elevational view thereof; and,

FIG. 6 is a rear elevational view thereof.

The portions of the flexible draw latch of the present invention shown in broken lines form no part of the claimed design.
